COMPOUND APPLICATOR FOR BUFFING MACHINES

Clifford I. Packer and Emil H. Kammerer, Meriden, Conn., assignors to The Packer Machine Company, Meriden, Conn., a corporation of Connecticut

Application March 2, 1940, Serial No. 321,926

20 Claims. (Cl. 51—263)

This invention relates to buffing and polishing machines, and more particularly to an improved automatic applicator for intermittently applying abradant buffing or polishing compound to a rotating buffing wheel.

One object of the present invention is to provide adjustable means for varying the amount of compound which will be applied to a buffing wheel at each stroke of the applicator in accordance with the requirements of the work being buffed.

A further object is to provide an applicator of the above nature having means to vary the number of strokes of the applicator in a given interval of time.

A further object of this invention is to provide a compound applicator of the above nature having means to automatically stop the feeding of the compound whenever it is substantially used up.

A further object is to provide an automatic applicator of the above nature having a holder for an elongated cake of compound, which holder is open at both ends to permit very long cakes to be employed.

A still further object of this invention is to provide an improved compound applicator of the above nature which will be relatively inexpensive to manufacture, easy to adjust, simple in construction, accurately controlled, compact, gentle in operation, economical of compound, and very efficient and durable in use.

With these and other objects in view, which will appear as the description proceeds, there has been illustrated in the accompanying drawings one form in which the invention may be conveniently embodied in practice.

In the drawings:

Fig. 1 illustrates a rotary buffing machine having an improved compound applicator of this invention installed thereon.

Fig. 2 is a side elevation on an enlarged scale of the compound applicator by itself.

Fig. 3 is an end view of the same.

Fig. 4 is a sectional view taken on the line 4—4 of Fig. 2.

Fig. 4A is a side view of certain parts shown in section in Fig. 4.

Fig. 5 is a sectional view taken on the line 5—5 of Fig. 3.

Fig. 5A is a view partly in section of an alternative construction of the feed screw shown in Fig. 5.

Fig. 6 is a sectional view taken on the line 6—6 of Fig. 3.

Fig. 7 is a sectional view taken on the line 7—7 of Fig. 2.

Fig. 8 is a diagram of the electrical circuits and controls for a buffing machine having three buffing wheels and applicators.

Referring now to the drawings wherein like reference numerals designate like parts throughout the several views, the numeral 10 (see Fig. 1) denotes the frame of the buffing and polishing machine having a rotatable table 11 mounted thereon, said table having a plurality of work holding spindles 12 upon its upper surface. The table 11 is adapted to be rotated by a motor 13 through gears 14, 15, shaft 16, and a pinion 17 in mesh with internal gear teeth 18 on the table 11, the motor 13 being started and stopped by push buttons 19 and 20 respectively.

A plurality of buffing or polishing wheels (three being herein shown) 21, 22 and 23 are arranged 20 about the table 11 upon suitable standards 21a, 22a and 23a, and are adapted to engage the work or articles to be buffed or polished, which are mounted on the spindles 12, the work being carried by said spindles successively past each of 25 the wheels 21, 22, and 23 by the slow rotation of the table 11. The wheels 21, 22 and 23 are driven by motors 24, 25, and 26 respectively, which are arranged to be started and stopped by push button switches 27, 28, 29, and 30, 31, 32 respectively.

Automatic applicators

The mechanism employed to apply the abrasive or polishing compound in the form of a rectangular semi-solid brick or block 33 to the polishing wheels 21, 22, and 23, is shown in Fig. 1—one such applicator being therein shown, but it is to be understood that similar applicators may also be provided in operative association with the buffing wheels 21 and 22.

Each compound applicator of this invention includes a rectangular base plate 34 which is herein shown secured to a stationary part of the machine (in this instance a journal 35 for the wheel shaft 36) by a suitable bracket 37 to which the plate 34 is shown secured by bolts 38. The journal 35, to which the plate 34 is secured, is adapted to be adjusted along with the respective buffing wheel 21, 22 or 23, to any desired angle, 45 it being understood that the three buffing wheels will usually be adjusted at different angles for engaging different parts of the work carried by the spindles 12.

Referring now more particularly to Figs. 2—7 50 inclusive, the stationary base plate 34 is shown

provided with two longitudinally spaced pairs of vertically depending lugs 39, 40 and 41, 42, the lugs of each pair being transversely spaced apart and adjacent the ends of the plate 34. Links 43, 44, 45, and 46 are pivotally connected one to each of the lugs 39, 40, 41, and 42 respectively by bolts 47. The links 43, 44, 45 and 46 extend upwardly and are pivotally connected by bolts 48 to a swingable angle plate 49—the links 43 and 44 being pivoted to lugs 50 and 51 respectively depending from the plate 49, and the links 45 and 46 being pivoted to the side flanges 52 and 53 respectively of a depending end portion 54 provided on the plate 49.

The plate 49 has a pair of transversely spaced apart arms 55 and 56 vertically upstanding from its forward end, and a pair of transversely spaced apart arms 57 and 58 vertically upstanding from its intermediate portion. The arms 55, 56 and 57, 58 are in longitudinal alinement and are adapted to slidably support and retain the block or brick of compound 33 upon the plate 49. A cover bar 59 extends across the top of the arms 55 and 56, being secured thereto by screws 60 to overlie the top of the compound brick 33.

In order to support the brick of compound in its intermittent reciprocations, provision is made of a pair of parallel longitudinally-extending pads 61 and 62 on the top of the plate 49 to support a brick clamping frame 63, U-shaped in cross section, the base 64 of which rides on the pads 61 and 62 and the sides 65 and 66 thereof extend upwardly and straddle the compound brick 33.

A cross bar 67, suitably guided by the upstanding sides 65 and 66, is adapted to seat upon the brick 33, and is pressed into clamping engagement therewith by a curved handle 68 which is pivoted by a pin 69 to a cover plate 70 extending across the brick 33 between the sides 65 and 66, being secured thereto by screws 71. The handle 68 has a cam-shaped end 72 which is adapted to engage a cross bar 73, also suitably guided by the sides 65 and 66, to press it downwardly to compress coiled springs 74 and 75, arranged to react between this bar and the cross bar 67 to force the latter tightly against the compound brick 33, and it in turn against the base 64 to clamp the brick 33 securely in the U-shaped frame 63. The brick-holding frame 63 in its longitudinal sliding movements on the plate 49 is guided by rods 76 and 77, one at either side of the frame 63, and which extend through holes 78 and 79 provided in the sides 65 and 66 thereof for this purpose. The rods 76 and 77 extend between and are suitably secured to the arm 55, 57, and the arms 56, 58 respectively by nuts 80.

Brick feed mechanism

The clamp frame 63 with the compound brick 33 clamped thereto is adapted to be fed forwardly step by step to compensate for the amount of the brick 33 worn off by the buffing wheel 21, 22 or 23, by means of a rotatable screw rod or shaft 81 having a threaded portion 82. The shaft 81 is journaled at its forward end in a bearing block 83 depending from the plate 49 and in an intermediate bearing block 84, which also depends from the plate 49.

The threaded portion 82 of the shaft 81 passes through a bracket 85 which is secured to the underside of the brick clamp frame base 64 by screws 86 and pins 87, said bracket 85 extending downwardly through a longitudinally elongated

opening 88 formed in the plate 49. A threaded half-nut 89 is mounted in a rectangular socket 90 in the bracket 85, and is adapted to partly surround the threaded portion 82 to have its threads cooperate therewith, whereby the intermittent rotation of the rod 81 will serve to feed the frame 63 forwardly in steps along the plate 49.

The half-nut 89 is constantly urged into tight cooperating engagement with the threaded portion 82 of the screw rod 81 by means of a spring 91 coiled about a shank 92 of a handle 93 and reacting between the half-nut 89 and the end wall 94 of the bracket 85. The shank 92 is pivotally secured to the half-nut 89 by a pin 95 which passes transversely through the half-nut 89 and rides in an annular groove 96 formed in the end of the shank 92. The end wall 94 has a boss 97 on its outer surface through which the shank 92 passes, which boss has a bayonet slot 98 formed in its outer end (see Fig. 4A), into which a pin 99, extending from the shank 92, is adapted to enter and seat, when the half-nut 89 is in place, to lock said half-nut in tight engagement with the threads 82 of the rod 81. The half-nut will thus be prevented from backing off or becoming disengaged from the feed screw.

When it is desired to release the half-nut 89 from its engagement with the threaded portion 82 of the shaft 81 so as to permit the brick-clamping frame 63 to be manually moved rearwardly to obtain another grip on the compound brick 33, it will only be necessary to twist the shank 92 about 90 degrees by means of the handle 93 to release the pin 99 from the bayonet slot 98, and then pull the half-nut 89 away from the screw-threaded portion 82. To hold the half-nut 89 in such released position, the shank 92 will again be twisted by the handle 93 to dispose the pin 99 upon the outer end of the boss 97.

The bracket 85 is shown in position (Fig. 4) to permit the handle 93 to extend outwardly from the left-hand side of the compound carrier plate 49, but it will be obvious that this construction may be reversed to permit the handle 93 to extend outwardly from the right-hand side if desired within the spirit and scope of the invention. This feature of the invention permits the applicators to be installed upon many different forms of buffing machines without interfering with other parts of the mechanism, and enables the applicators to be placed in convenient and accessible positions.

It will also be understood that due to the use of the links 43, 44, 45 and 46, and the plates 34 and 49, the brick 33 will move in an arcuate path—the plates 34 and 49 remaining parallel to each other at all times. To obtain this swinging reciprocating movement toward and away from the polishing wheel, a cam roller 102 is rotatably mounted at the lower end of the depending end portion 54 of the plate 49 by a pin 103 extending from and fastened in said end portion 54.

The roller 102 is arranged to travel between the opposing camming flanges 104 and 105 of a cam 106, which cam is keyed to the shaft end 107 of a feed motor 108, 109, 110 by a key 111, one motor being provided for each of the applicators for the polishing wheels 21, 22 and 23 respectively. The feed motors 108, 109 and 110 are each of the well-known type which are generally termed "ratio motors," and may include a speed reducer combined with a motor. The feed motors 108, 109 and 110 are suspended by their upper bases from the stationary plate 34 by means of bolts 112, and said motors are controlled by starting and stop-

ping push button switches 113, 114, 115, and 116, 117, 118 respectively.

The shape of the camming surfaces 104 and 105 is preferably made such that the movement of the compound brick 33 toward and away from the polishing wheel 21, 22, or 23 may be smooth and uniform or variable, as desired, and that said brick will impinge squarely against the respective polishing or buffering wheel a sufficient length of time to apply the desired amount of compound thereto.

In order to intermittently and automatically rotate the screw rod 81 at each successive stroke of the compound brick against the buffering wheel, provision is made of a spring-pressed pawl 119 which engages a ratchet wheel 120, secured by a key 121 to the adjacent rear end of the shaft 81. The pawl 119 is adapted to engage a tooth of the ratchet wheel 120 and intermittently rotate the shaft 81 at each forward movement of the compound carrying plate 49—the pawl 119 then being swung back about the ratchet wheel 120 to its original position by the rearward movement of said cam-driven plate 49.

This rocking action of the pawl 119 is obtained by mounting it upon one end of a lever 122, which (as shown in Fig. 7) is rotatably mounted upon the rear end of the shaft 81, the other end 123 of the lever 122 having a roller 124 which rides between the parallel flanges 125, 126 of a track 127 formed in the face of an adjustable angularly disposed swingable box member 128. The member 128 is adjustable angularly to vary the throw of the pawl 119, whereby the latter will swing over more or less of the teeth of the ratchet wheel 120 when the plate 49 moves rearwardly, and will thus serve to vary the amount the brick 33 is fed forwardly at each stroke of said plate 49. This is accomplished by pivoting the member 128 to a vertical flange 129 (see Fig. 2) formed on the stationary plate 34 by a screw 130 which passes through the flange 129 and screw-threads into the member 128. As most clearly shown in Fig. 2, another screw 131 also is screw-threaded into the member 128 and extends through an arcuate elongated slot 132 formed in the flange 129 for locking the member 128 in its angularly adjusted position.

In order to automatically stop the feed motor (108, 109, 110) whenever the U-shaped brick-holding frame 63 has reached its extreme forward position due to wearing off of the brick 33 by the buffering wheel, provision is made of a normally closed switch (133, 134 and 135), one on each device, and a forwardly protruding lug 136 on each clamp 63. The lug 136 is adapted, when the clamp 63 is in its extreme forward position, to engage the operating arm 137 of the respective switches 133, 134, or 135 to open the same, and thus stop the respective feed motors 108, 109, or 110.

It is also within the scope of this invention to automatically stop the feed of the compound brick 33 by removing or omitting a number of threads from the threaded portion 82 of the shaft 81, as shown at 100 in Fig. 5A. By means of this construction, when the compound brick clamping frame 63 reaches its extreme feeding position adjacent the vertical arms 55 and 56, the half-nut 89 will run off the threads of the threaded portion 82 and further feeding movement will be prevented. When this occurs, the operator will loosen the compound clamp by manipulation of the top curved handle 68, and by pulling on the handle 93, will draw the half-nut 89 away

from the threaded portion 82 of the shaft 81. The clamp 63 may then be moved rearwardly along the compound brick 33 as far as desired and again secured to the brick 33.

5

Electrical control apparatus

To simultaneously stop all of the compound feeding motors 108, 109 and 110 whenever for any reason the main machine motor 13 stops, and thus prevent further wearing off of compound by the buffering wheels, provision is made of solenoid-operated switches or relays 138, 139, 140 (see Fig. 8) as will be described later.

Means are also provided to separately control the period of operation of the respective feed motors 108, 109, 110 so as to vary the amount of compound applied to the different buffering wheels without changing the adjustment of the inclined box members 128. This is also shown in Fig. 8 and will be hereinafter more fully described.

In the electrical diagram of Fig. 8 the table-operating motor 13 is shown connected to the line wire L1 by a conductor 141 and by a conductor 142 to a solenoid-controlled switch or relay 143. The switch 143 is connected by a conductor 144 through the normally closed push button motor stopping switch 20 with the line wire L2. The feed motor stop switches 138, 139, 140, and 143 are all closed simultaneously by a solenoid 145 when it is energized by the closing of the normally open push button table-operating motor starting switch 19 which is connected by a conductor 146 to the line wire L2 and by a conductor 147 to one terminal of the solenoid 145, the other terminal of which is connected by a conductor 148 to the line wire L1.

To sustain the energizing circuit through the solenoid 145 when the push button 19 is released, the circuit from the conductor 144 passes through a switch 149 also controlled by the solenoid 145, and which is connected by a conductor 150 to the same terminal to which the conductor 147 from the push button 19 leads.

The applicator motor control switches 138, 139, and 140 controlled by the solenoid 145 are all connected to the line wire L2 by a common conductor 151, and said control switches 138, 139, 140 are joined to separate motor speed control devices of any standard form indicated by the numerals 152, 153, and 154, by conductors 155, 156, and 157 respectively. The control devices 152, 153, and 154 are connected by conductors 158, 159, and 160 respectively to the compound applicator feed motors 108, 109, and 110.

The motors 108, 109, and 110 are connected by conductors 161, 162, and 163 respectively to solenoid-controlled switches or relays 164, 165, and 166, which are in turn connected by conductors 167, 168, and 169 respectively to the normally closed push button motor stopping switches 116, 117, and 118. The feed motor switches 116, 117, and 118 are connected by conductors 170, 171 and 172 respectively to the line wire L1. The switches 164, 165, and 166 are controlled by solenoids 173, 174, and 175 respectively, which close said switches when energized. The solenoids 173, 174, and 175 are arranged to be energized by the normally open push button motor starting switches 113, 114 and 115 respectively by having one terminal of each of them connected to said solenoids by conductors 176, 177, and 178 respectively, the switches 113, 114, 115 being connected by conductors 179, 180 and 181 respectively to the line wire L1. The other terminals of the solenoids 173, 174, and 175 are connected by

75

conductors 182, 183, and 184 to the normally closed compound carrier movement limiting switches 133, 134, and 135 respectively, which in turn are connected to the line wire L2 by conductors 185, 186, and 187 respectively.

To maintain the solenoids 173, 174, and 175 in energized condition, provision is made of switches 188, 189, and 190, controlled by these solenoids respectively, and said switches are connected to the normally closed stopping switches 116, 117, and 118 by the conductors 167, 168, and 169, and to one terminal of said solenoids by conductors 191, 192, and 193 respectively.

It will be obvious from the above, that by pressing the normally closed motor stopping push button 20, the solenoid 145 will be de-energized, whereby the switch 143, controlling the table driving motor 13 and switches 138, 139, and 140, controlling the compound applicator motors 108, 109, and 110 respectively, will also be opened and all of these motors will instantly stop. It will also be evident that, if any one of the brick-operated stop switches 133, 134, and 135 is opened by the lug 136 and its associated frame 68, the respective solenoids 173, 174, and 175 will be de-energized to open the switches 164, 165, and 166 respectively to stop the respective motors 108, 109, and 110. Likewise, the manipulation of either of the normally closed switches 116, 117, or 118 will de-energize the respective solenoid 173, 174, or 175, to stop the respective feed motors 108, 109, and 110.

The buffing wheel motors 24, 25, and 26 are connected to the line wire L2 by conductors 194, 195, and 196 respectively and to solenoid operated switches 197, 198, and 199 by conductors 200, 201 and 202 respectively. The switches 197, 198, and 199 in turn are connected by conductors 203, 204, and 205 to the buffing wheel motor stopping push button switches 30, 31 and 32 respectively, which in turn are connected to the line wire L1 by conductors 206, 207, and 208 respectively. Solenoids 209, 210, and 211 control the switches 197, 198, and 199 respectively, and each has one of its terminals connected by a conductor 212 to the line wire L2. The other terminals of the solenoids 209, 210, and 211 are connected by conductors 213, 214, and 215 to the motor starting push button switches 27, 28, and 29 respectively, which in turn are connected to the line wire L1 by conductors 216, 217, and 218 respectively. To sustain the solenoids 209, 210, and 211 energized after the respective starting push button switches are released, provision is made of switches 219, 220, and 221 controlled by these solenoids, respectively. The switches 219, 220, and 221 are connected by conductors 222, 223, and 224 to the same solenoid terminal to which the conductors 213, 214, and 215 lead, and by the conductors 203, 204, and 205 to the motor stopping push button switches 30, 31, and 32.

Operation

In operation, the articles to be buffed or polished will first be placed on the work-holding spindles 12, and the buffing wheels 21, 22, and 23 adjusted to engage the same as the table 11 revolves. Bricks 33 of compound will then be placed on the carrier plates 49 and locked in the clamps 63 in their extreme rearward positions. The table motor 13 will then be started by pressing the push button 19. This closes the relay switch 143 to sustain the operation of the motor 13, and also the relay switches 138, 139 and 140 to operate the compound applicator or feed mo-

tors 108, 109, and 110. The buffing wheel driving motors 24, 25, and 26 will next be started by pressing the respective push buttons 27, 28, and 29. The applicator motors 108, 109, and 110 may next be started by pressing the respective motor push buttons 113, 114, and 115.

When the applicator feed motors 108, 109, and 110 are in motion, the cam 106 will continuously rotate to reciprocate the plate 49 and swing with it the compound brick 33 toward and away from the respective buffing wheel to apply compound thereto. The pawl 119 will actuate the ratchet wheel 120 on the screw rod 81 to intermittently feed the brick-holding frame 63 forwardly through the means of the cooperating half-nut 89. These operations will continue automatically until either the table motor 13 is stopped or the bricks 33 are substantially used up. If the table motor should stop, all of the compound applicator motors will also automatically stop, and when one of the bricks is substantially used up, the particular feed motor 108, 109, or 110 will be stopped by the engagement of the lug 136 on the clamp 63 with the arm 137.

If a more rapid feed for any particular brick is desired, it will only be necessary to adjust the swingable member 128 to a greater angle, whereby the pawl 119 will be caused to pass by a greater number of teeth of the ratchet wheel 120 and rotate the screw rod 81 a correspondingly greater amount. By means of the motor speed controls 152, 153, and 154, the motors 108, 109, and 110 may be driven faster or slower as desired, thus varying the reciprocating speed of the brick carrying plates 49 through the cams 106.

One advantage of the present invention is that the holder for the compound brick 33 may be readily replaced with a wider or narrower one according to the width of the buffing wheel.

A further advantage is in the use of swingable links 43, 44, 45, and 46, which greatly reduces the friction between the moving parts.

While there have been disclosed in this specification two forms in which the invention may be embodied, it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new and for which it is desired to obtain Letters Patent is:

1. In a buffing machine, a rotatable table having work-carrying spindles thereon, a plurality of buffing wheels disposed about said table and adapted to engage the work on said spindles, a compound applicator for each buffing wheel, a brick of abrasive compound carried by each applicator, means to reciprocate said bricks toward and away from the respective wheels to apply compound thereto, separate electric motors for reciprocating each of said compound applicators, separate control means to start and stop each of said motors, and interlocking switches in the circuits of said control means to stop all of said compound applicator motors simultaneously when said table is stopped.

2. In a buffing machine, a rotatable table having work-carrying spindles thereon, a plurality of buffing wheels disposed about said table and adapted to engage the work on said spindles, a compound applicator for each buffing wheel, a

brick of abrasive compound carried by each applicator, means to reciprocate said bricks to apply compound to their respective buffing wheels, separate electric motors for reciprocating each of said compound applicators, separate control means to start and stop each of said motors, separate electrical means in the circuit of each of the applicator motors to control the speed thereof, and means to stop simultaneously all of said compound applicator motors when said table is stopped.

3. In a buffing machine, a rotatable table having work-carrying spindles thereon, a plurality of buffing wheels disposed about said table and adapted to engage the work on said spindles, a compound applicator for each buffing wheel, a brick of compound carried by each applicator, means to reciprocate said bricks toward and from their respective buffing wheels to apply compound thereto at each stroke of said applicators, means to feed said bricks progressively farther on each successive stroke to compensate for the abrasive applied to the respective buffing wheels, separate electric motors for reciprocating each of said compound applicators, separate control means to start and stop each of said motors, and means controlled by the movement of each brick toward its respective buffing wheel to stop the respective applicator motor when a predetermined amount of said compound is exhausted.

4. In a buffing machine, a rotatable table having work-carrying spindles thereon, a plurality of buffing wheels disposed about said table and adapted to engage the work on said spindles, a compound applicator for each buffing wheel, means in each applicator to reciprocate a brick of compound toward and away from the respective buffing wheel to apply compound thereto at each stroke thereof, means to feed said brick progressively farther on each successive stroke to compensate for the compound applied to the respective buffing wheel, separate electric motors for reciprocating each of said compound applicators, switches to start and stop each of said motors, means responsive to the movement of each applicator toward its respective buffing wheel to stop its corresponding applicator motor when the brick has worn off to a predetermined length, and means to stop simultaneously all of said compound applicator motors when said table is stopped.

5. In a compound applicator for applying buffing compound to a rotatable buffing wheel, a stationary base plate, a movable compound-carrying plate, a plurality of links for pivotally connecting the corners of said movable plate to said base plate, and means to reciprocate and swing said movable plate in a curved path, said movable plate remaining parallel to said base plate at all times.

6. In a compound applicator for applying buffing compound to a rotatable buffing wheel, a stationary base plate, a movable compound-carrying plate, said movable plate being swingably supported on said base plate by a plurality of links pivotally connected to the sides thereof, a cam roller secured to said movable plate, a rotatable cam for reciprocating said roller, and an electric motor mounted on said base plate to drive said cam.

7. In a compound applicator for applying buffing compound to a rotatable buffing wheel, a stationary base plate, a movable compound-carrying plate, said movable plate being swingably supported on said first plate by two pairs of pivoted

links disposed at each end thereof, electric motor driven means to reciprocate and swing said movable plate parallel to said first plate, and means to advance the compound carried by said movable plate progressively farther at each stroke thereof.

8. In a compound applicator for applying a buffing compound to a rotatable buffing wheel, a stationary base plate, a movable compound-carrying plate, said second plate being swingably supported on said first plate by two pairs of links pivoted to both of said plates at each end thereof, electric motor driven means to reciprocate and swing said movable plate relatively to said base plate, means to feed the compound carried by said movable plate lengthwise progressively farther at each successive stroke of said movable plate including a screw rod, a ratchet wheel secured to said rod, a swingable pawl to rotate said ratchet wheel intermittently, and means mounted on said base plate for driving said pawl at each stroke of said movable plate to swing said pawl to rotate said ratchet wheel.

9. In a compound applicator for applying a buffing compound to a rotatable buffing wheel, a stationary base plate, a movable compound-carrying plate, said second plate being swingably supported on said first plate by two pairs of links pivoted to both of said plates at each end thereof, electric motor driven means to reciprocate and swing said movable plate relatively to said base plate, means to feed the compound carried by said movable plate lengthwise progressively farther at each successive stroke of said movable plate including a screw rod, a ratchet wheel secured to said rod, a swingable pawl to rotate said ratchet wheel intermittently, and lever and cam means mounted on said base plate for driving said pawl at each stroke of said movable plate to swing said pawl to rotate said ratchet wheel.

10. In a compound applicator for applying buffing compound to a rotatable buffing wheel, a stationary base plate, a movable compound-carrying plate, said movable plate being swingably supported on said first plate by a plurality of links pivoted to each plate, a cam roller carried at one end of said movable plate, a continuously driven rotatable cam for engaging said roller to reciprocate it and cause said movable plate to swing and reciprocate relatively to said base plate, means to feed the compound carried by said movable plate lengthwise thereof progressively farther at each stroke thereof, including a screw rod, a ratchet wheel secured to said rod, and lever and cam means mounted on said base plate to intermittently swing said pawl to rotate said ratchet wheel.

11. In a mechanism for successively applying abrasive or polishing compound to a buffing wheel, a frame, a reciprocating carrier for a brick of compound mounted in said frame, said carrier having a bracket secured thereto, an intermittently rotated screw rod journaled in said bracket, a nut sector movably carried in said bracket and having detachable engagement with said screw rod to permit the carrier to be moved rearwardly whenever it is necessary to replace an exhausted brick with a new one, and means to selectively lock the detachable nut sector either in or out of engagement with said screw rod, said carrier being open at both ends to permit the clamping of a brick of greater length than said carrier.

12. In a mechanism for successively applying

abrasive or polishing compound to a buffing wheel, a frame, a reciprocating carrier for a brick of compound mounted in said frame, said carrier having a bracket secured thereto, an intermittently rotated screw rod journaled in said bracket, a nut sector slidable in said bracket and having detachable engagement with said screw rod to permit the carrier to be moved rearwardly whenever it is necessary to replace an exhausted brick with a new one, a radial rod secured to said detachable nut sector, said rod carrying a pin, said carrier having a guide collar embracing said rod and having a bayonet slot for releasably receiving said pin, whereby said sector may be selectively locked either in or out of engagement with said screw rod.

13. In a mechanism for successively applying abrasive or polishing compound to a buffing wheel, a frame, a reciprocating carrier for a brick of compound mounted in said frame, a half nut slidable mounted in said carrier, an intermittently rotated screw rod fitted in said nut to cause said carrier to advance said brick progressively farther at each successive stroke, said nut being detachable from said screw rod to release the carrier whenever it is necessary to replace an exhausted brick with a new one, a radial rod pivotally secured to said detachable half nut, said rod carrying a pin, said carrier having a guide collar embracing said rod and having a bayonet slot for releasably receiving said pin, whereby said half nut may be selectively locked either in or out of engagement with said screw rod.

14. In a mechanism for successively applying abrasive or polishing compound to a buffing wheel, a frame, a reciprocating carrier for a brick of compound mounted in said frame, said carrier having a half nut slidable secured thereto, an intermittently rotated screw rod fitted in said nut to cause said carrier to advance said brick progressively farther at each successive stroke, said nut being laterally detachable from said screw rod to release the carrier for rearward movement whenever it is necessary to replace an exhausted brick with a new one, a radial spring-pressed rod secured to said detachable half nut, said rod carrying a pin, said carrier having a guide collar embracing said rod and having a bayonet slot for releasably receiving said pin, whereby said half nut may be selectively locked either in or out of engagement with said screw rod.

15. In a mechanism for applying abrasive or polishing compound to a buffing wheel, a frame, 55 a carrier for an elongated brick of compound

slidably mounted in said frame, said carrier including a U-shaped member for engaging the intermediate portion of said brick, and means in the top of said member to releasably clamp said brick therein, said carrier being open at both ends to permit the use of a brick of length greater than said carrier.

16. In a mechanism for applying compound to a buffing wheel, a frame for attachment adjacent said wheel, and a carrier for an elongated brick of compound slidably mounted in said frame, said carrier including a short detachable clamp for the intermediate portion of said brick, said carrier being open at both ends to permit the use of a brick of length greater than said carrier.

17. In a mechanism for applying compound to a buffing wheel, a frame for attachment adjacent said wheel, and a carrier for an elongated brick of compound slidably mounted in said frame, said carrier including a short detachable spring-pressed clamp for the intermediate portion of said brick, said carrier being open at both ends to permit the use of a brick of length greater than said carrier.

18. In a mechanism for applying compound to a buffing wheel, a frame for attachment adjacent said wheel, a carrier for an elongated brick of compound slidably mounted in said frame, said carrier including a short detachable clamp for the intermediate portion of said brick, and manually operated means to releasably lock said clamp in brick-clamping position, said carrier being open at both ends to permit the use of a brick of length greater than said carrier.

19. In a compound applicator for a buffing wheel, a frame for attachment adjacent said wheel, a carrier for a brick of compound slidably mounted in said frame, and motor and cam operated means to reciprocate said carrier to successively force said brick against said buffing wheel, said carrier being open at both ends to permit the use of a brick of length greater than said carrier.

20. In a compound applicator for a buffing wheel, a frame for attachment adjacent said wheel, a carrier for a brick of compound slidably mounted in said frame, and motor driven means to reciprocate said carrier to successively force said brick against said buffing wheel, said carrier being open at both ends to permit the use of a brick of length greater than said carrier.
